CLAIM

The ornamental design for a keeper for a rope halter, as shown and described.

DESCRIPTION

FIG. 1 is a left front perspective view of a keeper for a rope halter embodying my new design.

FIG. 2 is a side elevational view thereof, the opposite side being identical to the side shown.

FIG. 3 is an end elevational view thereof, the opposite end being identical to the end shown.

FIG. 4 is a top plan view thereof.

FIG. 5 is a bottom plan view thereof.

FIG. 1

FIG. 2

FIG. 3

FIG. 4

FIG. 5
